FIGURE 1 is a perspective view, from the front, of a portable shielded desk, showing my new design;

FIGURE 2 is a top plan view thereof;

FIGURE 3 is a perspective view from the rear thereof;

FIGURE 4 is a side elevational view showing the desk partially folded;

FIGURE 5 is a front elevational view thereof; and

FIGURE 6 is a perspective view of the desk completely folded for portability.

The design is characterized by the paired shelf and light arrangement in combination with the specifically configured side panels together with the compact appearance of the desk when converted to its portable position as best illustrated in FIGURE 6.

I claim:

The ornamental design for a portable shielded desk, as shown and described.
